UNITED STATES PATENT OFFICE.

GEORGE A. GLAHN AND GURDON W. HULL, OF WALLINGFORD, CONNECTICUT, ASSIGNORS TO THE WHITING MANUFACTURING COMPANY, OF NEW YORK, N. Y.

DESIGN FOR A SPOON OR FORK.

SPECIFICATION forming part of Design No. 21,169, dated November 10, 1891.

Application filed October 19, 1891. Serial No. 409,226. Term of patent 3½ years.

To all whom it may concern:

Be it known that we, GEORGE A. GLAHN and GURDON W. HULL, of Wallingford, in the county of New Haven and State of Connecticut, have invented a new Design for Spoon and Fork Handles; and we do hereby declare the following, when taken in connection with accompanying drawing, to be a full, clear, and exact description of the same, and which said drawing constitutes part of this specification, and represents a face view of the handle.

This invention relates to a design for the handles of spoons, forks, and like articles of table-service; and it consists in the configuration and ornamentation, as shown in the accompanying illustration.

The surface of the handle is ornamented by floriated scroll-work of Rococo character, the

handle gradually expanding toward the tip, the outline of the handle conforming to the 20 shape of the scroll-work. At the tip the surface within the scroll-work border is left plain to form a panel, as shown in the accompanying illustration.

We claim—

25 The design for spoon and fork handles, as herein described, and shown in the accompanying illustration.

In testimony whereof we have signed this specification in the presence of two subscribing witnesses.

GEORGE A. GLAHN.
G. W. HULL.

Witnesses.
